UNITED STATES PATENT OFFICE.

DE WITT C. WEBB, OF BOSTON, MASSACHUSETTS.

RADIATOR ATTACHMENT.

1,102,705.

Specification of Letters Patent. Patented July 7, 1914.

Application filed September 1, 1911. Serial No. 647,242.

To all whom it may concern:

Be it known that I, DE WITT C. WEBB, a citizen of the United States, residing at Boston, county of Suffolk, State of Massachusetts, have invented certain new and useful Improvements in Radiator Attachments, of which the following is a specification, reference being had therein to the accompanying drawing.

10 This invention relates to certain new and useful improvements in radiator attachments and more particularly to an air moistener for increasing the humidity in houses where radiators are used, the object 15 being to provide an air moistener which is provided with an evaporating tank and a feed tank, the evaporating tank being automatically supplied with water from the feed tank.

20 Another object of the invention is to provide the evaporating tank with a wick which will be constantly maintained in a moist condition by capillary attraction in order that the hot air circulating from the 25 radiator will be thoroughly moistened.

A further object of the invention is to provide an evaporating tank with a perforated inner wall in order to allow the heat to circulate through the tank in order 30 to moisten the air.

A still further object of the invention is to provide a feed tank with a valve which is automatically opened and closed by a float mounted within the evaporating tank 35 whereby the water will be maintained at a stated level within the tank.

Other and further objects and advantages of the invention will be hereinafter set forth and the novel features thereof defined by 40 the appended claims.

In the drawings—Figure 1 is a side elevation of the upper portion of a radiator showing the application of my improved air moistener the evaporating tank being 45 broken away to show the construction of wick and inner wall of the same; Fig. 2 is a vertical section taken on line 2—2 of Fig. 1; Fig. 3 is a vertical section taken on line 3—3 of Fig. 1; Fig. 4 is a side elevation of a 50 radiator showing a slightly modified form of moistener, the same being broken away in order to show the construction of the interior; and Fig. 5 is a section taken on line 5—5 of Fig. 4.

55 Like numerals of reference refer to like parts in the several figures of the drawings.

In the drawings, 1 indicates a radiator of the ordinary construction formed of a plurality of sections between which are arranged plates 2 carrying bolts 3 for securing the supporting brackets 4 in position on the side of the radiator, said brackets being preferably of the shape as shown so as to clamp the body of the evaporating tank 5 firmly in position. The evaporating tank 5, as shown, is provided with an extended inner wall 6 which is corrugated and perforated so as to form a deflector which extends above the top of the radiator sections and is adapted to deflect the heat outwardly, this construction being especially adapted to be used when the radiator is placed close to a wall. The tank 5 is provided with a hinged cover 7 which extends upwardly parallel to the deflector and is 75 adapted to rest upon a wick 8 arranged within the tank and between the cover and deflector as shown, said wick being held moist by capillary attraction in order to thoroughly moisten the heated air radiating 80 from the radiator. It will be seen that by forming the wall of the deflector corrugated and perforated, the heated air is allowed to act upon the wick so as to cause evaporation.

One end of the tank 5 is provided with 85 an extended portion 9 over which extends an over-hanging portion 10 of a feed tank 11 arranged on the end of the radiator and supported by a bracket 12, said tank being adapted to be supplied with water from any 90 source of supply. The abutting walls of the feed tank and the extended portion 9 of the evaporating tank are provided with registering openings forming a port 13 closed by a valve 14 carried by a rod 15 pivotally 95 mounted in a bracket 16 and provided with a rod 17 to the upper end of which is loosely connected a float 18 in order to automatically open and close the port 13 so as to maintain the desired water level within the 100 evaporating tank. By this construction, the evaporating tank will be supplied with water automatically from the feed tank as the same is evaporated therefrom which will avoid the filling of the evaporating tank by 105 hand and by forming the feed tank of a sufficient size, it will only be necessary to refill the same once a month.

In the modification shown in Fig. 4, the evaporating tank 19 is supported on the side 110 of the radiator by brackets 20 in a similar manner and is provided with an extended

inner wall to form a deflector corrugated and perforated as shown at 21 for its entire height and, as shown, the evaporating tank is arranged in a lower horizontal plane than 5 in the preferred form which allows a free circulation of the heat and air to pass between the wall of the evaporating tank and the faces of the radiating sections. In this form, the upper edge of the inner wall or 10 deflector is extended slightly in the reverse direction against which the edge of the perforated cover 22 is adapted to abut, which forms the outer wall of the deflector and it will be seen that this deflector completely 15 incloses the tank, the perforated cover and wall allowing the air to circulate through the deflector in order to moisten the same. One end of the evaporating tank extends 20 out beyond the end radiator section and mounted upon said extended end is a feed tank 23, the abutting walls of the respective tanks having registering openings a port 24 which is closed by a valve 25 pivotally connected to the pivoted lever 26 mounted in 25 an arm 27 and provided with a slotted end 28 in which is slidably mounted a pin 29 carried by the upper end of a rod 30 which extends through a stuffing box 31 and carries 30 a float 32 at its lower end mounted within the evaporating tank in order to maintain the water at the desired height in the evaporating tank. Arranged longitudinally within the top of the tank is a feed trough 35 33, one end of which is arranged under the port 24 into which the water from the feed tank is adapted to be discharged when the valve 25 is opened and from which the water is adapted to overflow on to a wick 34 arranged against the corrugated wall of the 40 evaporating tank, the upper edge of said wick being arranged within the feed trough and by this construction, every time the valve 25 is raised by the dropping of the float, the wick will be moistened, the sur- 45 plus water passing into the tank.

While I have shown and described the walls of the tank as corrugated and perforated in a certain manner, it is, of course, understood that in some cases, better results 50 may be obtained by dispensing with such corrugations and perforations upon one wall and that instead of using a fabric wick, any suitable porous material, such as unglazed terra cotta, may be used.

Having described my invention and set forth its merits what I claim and desire to secure by Letters Patent is:—

1. A radiator attachment comprising an

evaporating tank having a perforated ex- 60 tended wall adjacent the radiator to which it is attached to form a deflector, a wick arranged over said deflector, a feed tank, and means for supporting said tanks at right angles to each other on the side and end of the radiator respectively. 65

2. A radiator attachment comprising an evaporating tank having an extended per- 70 forated inner wall to form a deflector, and a wick supported within said tank extending onto said deflector.

3. A radiator attachment comprising an evaporating tank provided with a deflector extending upward therefrom having spaced 75 perforated walls, and a wick arranged between said perforated walls.

4. A radiator attachment comprising an evaporating tank having an extended corrugated and perforated wall forming a deflector, and a wick arranged in said tank ex- 80 tending over said deflector.

5. An attachment for radiators comprising an evaporating tank having an extended end portion, a feed tank having an over- 85 hanging portion, the abutting walls of said tanks being provided with registering open- 90 ings forming a port, a valve for closing said port, and a float mounted in said evaporat- 95 ing tank for actuating said valve.

6. The combination with a radiator, of an evaporating tank connected therewith, a feed tank, means for automatically sup- 90 95 plying liquid from the feed tank to the evaporating tank, and a wick arranged within the evaporating tank against the wall adjacent the radiator.

7. An air moistening device for radiators comprising a water vessel provided with a substantially horizontal extension connected with the water vessel and having an open bottom, absorbent material upon the exten- 100 sion and covering substantially the area thereof and extending down into the water receptacle, to convey moisture to the upper portion of the absorbent material by capillary attraction, and means carried by the 105 device for supporting the same upon a radiator with the water vessel in an upright position at one side of the radiator with the extension lying across the top of the radiator. 110

In testimony whereof I affix my signature in presence of two witnesses.

DE WITT C. WEBB.
